UNITED STATES PATENT OFFICE.

OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

CARRIAGE-RETURN MECHANISM.

1,120,862.

Specification of Letters Patent. Patented Dec. 15, 1914.

Application filed August 7, 1911. Serial No. 642,888.

To all whom it may concern:

Be it known that I, Otto THIEME, a citizen of the United States, residing at St. Louis, Missouri, have invented a certain new and useful Improvement in Carriage-Return Mechanisms, of which the following is a full, clear, and exact description, such as will enable others skilled in the art to which it appertains to make and use the same, reference being had to the accompanying drawings, forming part of this specification, in which—

Figure 1 is a rear elevational view of my improved carriage return mechanism. Fig. 2 is a vertical sectional view of the same. Fig. 3 is a detail view of the same. Fig. 4 is a detail view through the clutch mechanism. Fig. 5 is a detail showing the means for locking the clutch mechanism.

This invention relates to new and useful improvements in carriage return mechanisms for typewriters and the like, the object being to operate the carriage return mechanism by a continuously running motor.

My improvement is designed especially for use in connection with the combined adding and calculating machine disclosed in French Patent No. 383,719, dated January 16, 1908, which is also shown in application for United States Letters Patent No. 310,739, filed April 9, 1906.

My invention consists in providing means whereby upon the depression of a key, a clutch is operated to place the carriage under control of the continuously running motor, whereby said carriage is returned, and in approaching and reaching its normal position at the left, said carriage operates means to automatically disengage the motor from the carriage.

In the drawings, 1 indicates the frame of a machine, 2 shows the carriage traveling upon suitable ways, and 3 is a platen provided with the usual ratchet for line spacing the paper, with which coöperates a feed pawl 4. 5 is a rack, mounted upon a laterally movable carriage, and with which coöperates a pinion 6 on the upper end of a shaft 7, mounted in suitable bearings on the frame of the machine. This shaft 7 carries an escapement wheel 8, with which coöperates the usual escapement pawls 9. In the normal operation of letter spacing, the escapement mechanism is operated either by

the space key or one of the letter keys, so as to permit the carriage to move one step leftwardly under the impelling action of a spring arranged in a drum 10, and connected to the carriage by means of a cable 11 in a manner well known.

The lower end of shaft 7 carries a clutch member 12 (see Fig. 2), which member co-operates with a companion member 13 slidably mounted upon the upper end of a shaft 14. Shaft 14 is rotated continuously by means of a motor 15 and appropriate gearing, as shown in Fig. 2, in a direction that when the clutch members 12—13 are coupled, the pinion 6 meshes with the rack 5 and moves the carriage toward the right, to restore it to normal position. The clutch members 12—13, shown as interlocking members, are housed in a slotted sleeve 16, forming a bearing for the upper end of shaft 14, said sleeve containing anti-friction rollers 17 so as to permit rod 19 to lift said sleeve without binding or cramping the parts. Sleeve 16 is provided with a circumferential groove in its lower portion, which coöperates with a bifurcated plate 18, in the bifurcation of which said sleeve rotates, said plate being mounted upon the lower end of a rod 19, guided in its vertical movement in suitable ways, and whose upper end is beveled as shown.

20 indicates a rod supported by the frame of the machine, and having a collar 21 adjustably mounted thereon near its lower end. Below this collar, a block 22 is slidably mounted on the rod, which block forms the pivotal bearing of a lever 23 having one end rounded and extending under the plate 18. A spring 24 bears under block 22, the lower end of said spring being seated upon a plate 25, adjustable with respect to block 22 by means of the nuts 26. In this manner, the compression of spring 24 may be regulated. Spring 27 connected to lever 23 tends at all times to lift the outer end of said lever and depress its inner end, in which depressed position of the inner end, the clutch members 12—13 are disengaged. 28 indicates a rod connected to a key lever 29, on the forward end of which is a key 30, preferably marked "Car. ret.", meaning "carriage return." In this manner, whenever the key 30 is depressed, the lever 23 is operated to raise the clutch member 13 into coöperative relation with the clutch member 12.

Shaft 7 has the clutch member 12 fixed to its lower end, and said shaft, as shown in Fig. 4, bears on the upper end of shaft 14. The upper end of shaft 14 is flattened where it passes between the rollers 17, so that the slotted collar will be caused to rotate with the shaft. The clutch member 13 is clamped in the slotted collar by means of a set screw 13^a, and is thus carried up into engagement with the clutch member 12 whenever the slotted collar is raised. When the slotted collar is raised, the flattened upper end thereof still maintains driving engagement with the roller 17 mounted in the slotted sleeve. As the carriage moves toward the right, an adjustable block 31 mounted thereon, through the medium of a pin 32 carried thereon, comes in contact with a sliding plate 33, mounted by means of a slot and pin connection upon the frame of the machine and normally held retracted by means of a spring 34. One end of this plate 33 is provided with an inclined portion 33^a, which is normally displaced with respect to the upper end of shaft 19 by means of the spring 34. When, however, the carriage moves to the right (or leftwardly in the rear view shown in Fig. 1), the pin 32 engages the plate 33 and moves the same over the end of the shaft 19, so as to depress the shaft 19 and disengage the clutch members 12-13. When the clutch member 12 is depressed, and the bottom wall of the plate 33 lies over the shaft 19, as shown in Fig. 2, any effort to operate the carriage return key 30 will only result in compressing spring 24 which supports the block in which lever 23 is mounted. When the carriage starts leftwardly, either by operation of the space key, a letter key or one of the tabulator keys, the bar 19 is released in readiness for another operation.

In order to hold the rod 19 elevated or depressed, and consequently the clutch members 12-13 in or out of operative engagement, I provide the upper end of rod 19 with two circumferential grooves 19^a, with which co-operates a spring pressed plunger 19^b, the spring behind said plunger being regulated by a screw 19^c.

To automatically effect a line space when the carriage is spaced leftwardly, I extend the lever 4^a, on which the platen feed pawl is mounted, rearwardly, as shown in Figs. 1 and 2, so that the rear end of said lever will, when the carriage is in such position that the lever lies to the left of the winged cam or plate 35, ride up over the inclined face of said plate as the carriage is moved toward the right, and operate the paper feed pawl. The winged cam or plate 35 is pivoted upon a shaft 36, mounted on the frame of the machine, and normally lies rearwardly and to one side of the path of

the projection on lever 4^a, as shown in Fig. 3. In this manner, it is possible to operate the typewriting mechanism in the usual way, by manually effecting the line spacing. Whenever the carriage return key is operated, however, the winged plate 35 is swung forwardly in the path of the projection 4^a, so as to automatically line space the paper. This is advantageous in operating the platen to list a series of numbers in column order, automatically returning the carriage at each operation and simultaneously effecting a line spacing thereof. The means for swinging the plate 35 into the path of the lever 4^a, consists of a dependent rock arm 37, having a cam projection 37^a thereon, which cam projection cooperates with a cam projection on the upper end of a bar 37', carried by an arm 38 fixed on the end of a sleeve 39 mounted on a shaft 40. The opposite end of this sleeve carries an arm 41, whose end is bifurcated and engages the plate 18. In this manner, whenever the clutch 12-13 is thrown into engagement, the arm 37 is raised, and the winged plate 35 moved into the path of the pawl lever 4^a, to effect line spacing. In order to hold the winged plate normally out of the path of the lever 4^a, I provide same with a flat leaf spring 35^a as shown in Fig. 3, which engages the pawl race rail with which the traveling carriage co-operates. The upper end of the winged plate is also provided with a pin 35^b, to space the same from the pawl race rail and properly position it with respect to the lever 4^a. The winged plate is loosely mounted on shaft 36, and straddles a collar 37^b fixed to said shaft, said collar being notched, as shown in Fig. 3, to receive the lower free end of the flat leaf spring yieldingly, and rock the winged plate with the shaft. If the pawl carrying lever 4^a should lie in front of the winged plate at a time when the carriage return key was depressed, the said winged plate would be arrested in its forward movement by contacting with the lever 4^a, but such arrest of the winged plate would not interfere with the continued rocking movement of the shaft 36, which rocking movement would be permitted by the lower end of the lever spring yielding under the movement of the collar 37^b. When the carriage return key was released and the parts restored to normal position, the winged plate would occupy a position to the rear of the path of travel of the lever 4^a as usual, due to the action of the lower end of the flat leaf spring re-establishing the normal operative position between the collar 36^a and said winged plate. The left-hand end of the winged plate 35 is preferably flared rearwardly, so that in the event it should be in its normal position at a time when the carriage is being moved leftwardly, the pawl 130

lever 4^a will displace said winged plate and move past the same.

43 is a bell crank lever mounted in the frame and having one of its arms connected by a rod 45 to the lever 41. A plate 44 is located behind the depending arm of the bell crank lever 43, and to said plate are connected rods, one of which is shown marked 42. The arrangement of these parts 10 is such that when the rod 42 is drawn forward, the plate 44 is moved up behind the bell crank lever 43 to prevent the same from rocking, in which position, by means of the rod 45, the bell crank lever 43 holds the 15 lever 41 down and the clutch disengaged.

What I claim is—

1. The combination of a paper carriage and its escapement mechanism, comprising a rack on the carriage, a pinion meshing 20 with the rack, a shaft on which said pinion is mounted, an escapement wheel on said shaft and pallets coöperating with said escapement wheel, and a carriage return mechanism comprising a continuously running 25 shaft in alinement with said first mentioned shaft, clutch members on said two shafts, and means for throwing said clutch members into and out of engagement.

2. The combination of a laterally movable 30 carriage, a spring for moving the same in one direction, an escapement mechanism for controlling the action of said spring, a driven clutch member carried by said escapement mechanism, a continuously running 35 motor, a driving clutch member in juxtaposition to said driven member, a motor for operating said driving member, and means for moving said driving member into engagement with the driven member, 40 whereby the carriage is restored to normal position by the motor against the energy of the carriage spring.

3. The combination of a paper carriage, its rack and pinion, of a shaft on which said 45 pinion is mounted, a clutch member on the lower end of said shaft, a continuously rotating shaft in alinement with the first mentioned shaft, a sleeve mounted on the end of said continuously rotating shaft, said sleeve 50 rotating with said shaft, but having a movement longitudinally the shaft, a clutch member carried by said sleeve and means for moving said sleeve and its carried clutch member lengthwise the rotating shaft.

55 4. The combination of a paper carriage, its rack and pinion, of a shaft on which said pinion is mounted, an escapement mechanism coöperating with said shaft, a clutch member arranged on the lower end of said shaft, 60 a constantly rotating shaft in alinement with said first mentioned shaft, a clutch member slidily mounted on the upper end of said constantly rotating shaft, a sleeve in which said last mentioned clutch member is mounted, rollers carried by said sleeve for coöper-

ating with the flat faces of said rotating shaft, and means engaging the sleeve for moving the same and its carried clutch member longitudinally the shaft.

5. The combination of a paper carriage, a continuously running motor, a clutch mechanism interposed between said motor and said carriage, means for engaging said clutch mechanism whereby the carriage is restored to normal position, means on the clutch mechanism for holding it in engagement, means coöperating with the clutch engaging mechanism to disengage the clutch, and means mounted on the carriage for operating said last mentioned means. 80

6. The combination of a paper carriage and its escapement mechanism, of a continuously rotating clutch member for reversely rotating a portion of said escapement mechanism, means for moving said driving clutch 85 member into operative position to effect such reverse rotation, means on said clutch for retaining it in operative position, and means on the carriage for actuating said clutch operating mechanism to disengage said clutch in a pre-determined position of the carriage.

7. The combination of a paper carriage, of a carriage return mechanism therefor, of a line spacing mechanism, a hinged plate 95 normally out of the path of movement of said line spacing mechanism, and means for connecting said hinged plate with said carriage return mechanism, whereby the hinged plate is moved into coöperative position, 100 with respect to the line spacing mechanism, when the carriage return mechanism becomes effective.

8. The combination of a paper carriage, a carriage return mechanism therefor, a line 105 spacing mechanism, a hinged plate, a shaft, on which said hinged plate is yieldingly mounted, and means for rocking said shaft and moving said hinged plate into the path of movement of said line spacing mechanism. 110

9. In a carriage return mechanism, a continuously rotated shaft, a second shaft axially alined therewith, and adapted to engage the carriage, and clutch mechanism 115 adapted to operatively connect said shafts.

10. The combination of a paper carriage, carriage return mechanism, a clutch therefor, line spacing mechanism, a cam plate for actuating the line spacing mechanism, 120 and means for simultaneously moving the clutch and the cam plate into operative position.

11. The combination with a paper carriage and its escapement mechanism, of a 125 continuously running motor, a clutch interposed between said motor and said escapement mechanism for engaging the two to return the carriage to normal position, operating means for the clutch, and an adjust- 130

- able member coöperating with the said operating means and adapted to yield when the operating means is operated while the clutch is retained in inoperative position.
5. 12. In combination, a paper carriage, a rack carried thereby, a pinion meshing with said rack, a continuously running motor, a clutch interposed between said motor and said pinion, a lever for operating said clutch, 10 and an adjustable fulcrum for said lever.
13. In combination, a paper carriage, a continuously running motor, a clutch mechanism interposed between said motor and said carriage, operating means for engaging 15 said clutch mechanism whereby the carriage is restored to normal position, means for holding the clutch mechanism out of engagement under predetermined conditions, and a flexible means coöperating with the operating means and adapted to yield under pressure exerted upon the operating means.
20. 14. The combination of a paper carriage, means for moving said carriage laterally in one direction, a continuously running motor geared to move said carriage in the opposite direction, a clutch interposed between said motor and said carriage, operating means under control of the operator for throwing 25
- 30 said clutch into operative position, means for preventing said clutch from being thrown into operative position when the carriage is home, and a yielding means coöperating with the operating means and adapted to receive stresses therefrom.
35. 15. In a carriage return mechanism, a clutch, means for operating the clutch, and flexible means coöperating with said operating means and adapted to yield under stress therefrom when the clutch is held in inoperative position.
40. 16. In a writing machine, the combination of a paper carriage, a carriage return mechanism therefor, a line-spacing mechanism on said carriage, a cam for actuating said line-spacing mechanism on return movement of the carriage, and a key for rendering said carriage return mechanism effective and for moving said cam to operative position.
45. In testimony whereof I hereunto affix my signature in the presence of two witnesses, this 5 day of August, 1911.

OTTO THIEME.
